GAS FIRED WATER HEATER

Filed May 17, 1951

UNITED STATES PATENT OFFICE

2,684,054

GAS FIRED WATER HEATER

Hiram J. Carson, Omaha, Nebr.

Application May 17, 1951, Serial No. 226,797

5 Claims. (Cl. 122—17)

1

The invention relates to gas-fired water heaters of the storage type, and has for its objects to provide certain new and useful improvements in water heaters of this character.

The water heater comprising the present invention is of the general character and operative principle disclosed in my co-pending application Serial No. 776,087, filed September 25, 1947, now Patent No. 2,563,817, for Gas Fired Water Heaters, but is designed to provide certain new and useful improvements and structural refinements thereover. For example, the instant improved water heater is designed to provide more rapid and uniform heating of the water within the storage tank, and also provides for burning gas in very large volume with high efficiency.

An important object of the present invention is to provide a gas-fired water heater unit of the storage type with a heating tube extending through the tank, wherein provision is made for a combustion space within the said heating tube, said combustion space being disposed immediately below a convection type of heat transfer unit within said heating tube. Said heating tube for practical and economical purposes may be of uniform diameter throughout its vertical extent within the interior of the water tank.

A further object of the invention is to provide an improved heat transfer unit of the convection type, the body of which is of lesser cross sectional area than that of said heating tube, and which may be cylindrical or conical, such as a truncated cone having vanes disposed at an angle to the vertical on the exterior thereof, said vanes preferably being of relatively light and economical construction. For example, said element may be preferably substantially hollow with its lower end closed, and formed of either sheet metal or of non-metallic heat resisting material, such as refractory material. Said heat transfer element is also designed for either permanent or adjustable mounting or support upon the gas burner unit, which latter is disposed below the central heating tube of the tank, or it may be supported from the floor or any other desirable and appropriate manner within the heater, so as to removably dispose the transfer element at the most desirable or prescribed locality in any way desired.

The invention contemplates the provision of a commodious lower chamber within the heater, said chamber being in open communication with the lower end of the central heating tube within the water tank and providing for the admission of air as necessary for supporting combustion.

A further object of the invention is to pro-

2

vide an improved gas-fired water heater of high capacity and efficiency wherein provision is made for substantial increase in the transfer of heat by convection to the lower portion of the central water tube of the heater tank.

Numerous other objects and advantages of the invention will be apparent as it is better understood from the following description which, taken in connection with the accompanying drawings, discloses a preferred embodiment thereof.

In said drawings:

Fig. 1 is a central vertical section through the improved water heater, certain parts thereof being shown in elevation.

Fig. 2 is a horizontal sectional view on line 2—2 of Fig. 1, and upon a slightly enlarged scale.

Fig. 3 is a similar view taken on line 3—3 of Fig. 1.

Fig. 4 is an enlarged detail view taken substantially on line 4—4 of Fig. 3, showing a manner of supporting the heat transfer convection unit on a conventional type of gas burner; said view also illustrating a manner of supporting the burner unit within the lower portion of the heater casing.

Referring to the drawings, the improved water heater comprises an insulated enclosing housing 9 including an outer cylindrical shell or casing 10 and an inner shell or casing 11 spaced therefrom. The outer casing is provided with an outer circular top portion or plate 12 and an inner circular member 13 spaced therefrom. The heater further includes a bottom portion or base plate member 14 having a peripheral flange 15 suitably secured to the outer casing 10, and having a central aperture 16 for the purpose of admitting air to the combustion space or chamber of the heater.

The space between the outer wall portions 10 and 12, and the inner wall portions 11 and 13 above 14 is preferably filled with a suitable heat-insulating medium 17 of any desired or approved material, such as cork, asbestos, rock wool, or the like.

The water heater proper comprises a tank 18 of substantially annular cross-section, including an outer cylindrical shell 19 and an inner tube 20 spaced therefrom to define therebetween a water chamber 22, said tube constituting an uptake passage for combustion products. Said water tank further includes a top wall portion 23 which is or may be provided with an outer covering 24 of insulating material. The bottom end of the outer water shell 19 may be suitably

secured as indicated at 19a to the base plate member 14 of the heater unit or by equivalent means. The water tank is also provided with a wall portion or member 25 constituting the bottom head of the tank. A substantially enclosed lower chamber 26 is disposed below the tank proper, which chamber may be surrounded by the extension of wall 19 of the heater tank or by equivalent means. Access to said lower chamber is afforded by means of an opening 26a in the heater casing which is normally closed by a pair of hinged doors 26b preferably disposed at the front of the heater. A suitable drain outlet pipe for the water tank 18 is shown at 25a.

The described structural elements of the heater are preferably supported by suitable peripherally spaced legs 27a and thereby provide for ready access of air therebetween for supporting combustion in the burner chamber of the heater.

The annular space 28 between the water tank 18 and outer insulated shell of the heater constitutes a downtake passage for products of combustion which escape through the usual flue outlet 29 having a conventional hood element 30 and discharge pipe 31 leading to the chimney or vent to the outside atmosphere.

The water to be heated in chamber 22 of the tank 18 is admitted through an inlet pipe 32 extending to near the bottom of the tank, and heated water is discharged from the tank through an outlet pipe 33 communicably connected with the top of the tank.

A conventional thermostat element 32a for automatic control of the heater in accordance with temperature conditions within chamber 22, is located in and communicates with said chamber through suitable apertures in the heater casing and tank, as best seen in Fig. 2.

A gas burner element is indicated at 34 and is mounted in the upper portion of the lower heater chamber 26. For this purpose said burner may include a pair of depending recessed lug elements 35 adapted to rest upon a transverse rod or support bar 36 secured at its opposite ends to the depending wall 19 of the water tank or by equivalent means. As illustrated said gas burner is provided with a pair of circular burner ports 37 arranged in concentric spaced relation and communicably connected to a gas and air inlet mixing tube 38. The gas supply pipe for the burner is shown at 39. The flared outer end of the mixing tube 38 may project through a pair of complementary semi-circular apertures 39a in the hinged doors 26b or be equivalently located. Said apertures permit opening and closing of said doors so said doors may be opened when desired to obtain access to the interior of the heater.

The combustion space or chamber of the heater is indicated at 27 and is located substantially within the lower portion of the central heating tube 20 immediately above the top of the gas burner 34, as is best seen in Figs. 1 and 4. By disposing the combustion space in this locality some of the heat resulting from products of combustion from the burner, is directly communicated through the tube wall into the lower portion of the annular water tank chamber 22.

The heat transfer convection element is indicated at 40 and is preferably supported by a spindle 41 resting on a transverse element 41a of the gas burner element 34. To this end said spindle 41 may be threaded and loosely projecting at its upper end through a central aperture

5 42 in the lower preferably conical wall 43 of the body of the heat transfer element which may be a substantially cylindrical or conical and hollow body member designated at 44 which preferably nests closely within the heating tube so as to be vertically adjustable therein and readily insertable thereinto. The lower end of the spindle 41 is adapted to be freely supported by the transverse rod or brace element 41a extending transversely across the central air inlet aperture 34a of the burner 34 (Fig. 4). The spindle 41 may be designed to support the element 40 in a permanent location or a nut 45 may threadedly engage the spindle 41 and through the medium of an intervening washer element, serve to support the body 44 of the heat transfer element 40 in vertically adjusted position within the lower end of the heating tube 20. In this manner the volume of the combustion space 27 in 10 the lower portion of the heating tube 20, and disposed between the heat transfer element and the gas burner 34, may be varied as desired in accordance with operating conditions to obtain the desired heat output from the burner to be 15 imparted to the water through the heating tube 20.

The heat transfer or convection element 40 may be of light weight and capable of economical manufacture. To this end the body of the 20 element which may be hollow and cylindrical or conical, may be constructed of sheet metal as illustrated, or other heat resisting or refractory material.

To provide the necessary swirling movement 35 of the hot gases of combustion from the burner, the body of the heat transfer element 40 is provided with a series of exteriorly disposed helical flutes, fins or vanes 46, which may be integrally formed therewith, and which flutes extend outwardly from the transfer element to terminate in closely spaced relation to the inner wall surface of the vertical heating tube 20. If desired the heat transfer element may be constructed of other non-metallic heat resistant materials, 40 or appropriate refractory substances. Conceivably the element may be cast as a unit of Pyrex or other glass material which may permit of 45 economic advantages.

The described construction and location of 50 the heat transfer element within the water heater serves to provide an adequate variable and full combustion space 27 above the burner and below the heat transfer element 40, said space and element being substantially entirely contained within 55 in the heating tube 20. It is in this described locality that a substantial amount of heat is imparted to the water for providing relatively uniform temperatures throughout the tank.

The hot products of combustion from the 60 burner are swirled exteriorly around the heat transfer element 40 into intimate contact with the wall of heating tube 20 and thereafter these gases continue rising and escape through the upper end of the uptake passage or heating tube 65 20 at the top of the tank. Thence the heated products of combustion pass radially outwardly through the horizontal space or passage over the top of the water tank and thereafter travel downwardly through the substantially restricted annular space or downtake passage 28 between the tank 18 and the inner wall 11 of the outer insulated housing 9. These hot products of combustion in their downward passage serve to further 70 75 heat the water in the tank to substantial uniform

temperature until the spent products are finally discharged through the aforesaid flue outlet 29.

From the foregoing it will be observed the water in the tank 18 is heated with very high efficiency and to relatively uniform temperature. This is due in part to the spiral flutes or vanes 46 extending transversely of the heat transfer element 40 which serve to transfer a substantial part of the heat in the initially heated products of combustion from the burner to the inner tank wall in the tube 20. Thereafter these heated combustion products travel upwardly and thereafter pass over the top of the tank and thence downwardly through the annular downtake passage 28 to further heat the water quickly and with great dispatch, prior to final escape of said combustion products through the flue outlet 29 in the casing 9.

The provision of the insulating material 24 over the top of the water tank 18 is optional and is primarily designed to prevent too rapid heating of the water in the upper portion of the tank as compared to that in the lower portions of the tank. The instant described manner of providing a combustion space within the tube 20, coupled with the variable or adjustable spacing of the heat transfer element 40 materially above the burner 34, has been found to virtually render unnecessary the provision of such top tank insulation.

For the purposes of the invention it is not necessary that the heat transfer or convection element 40 be mounted on the burner as illustrated and described. For example, said element may be removably secured in any desired manner within the heating tube 20.

Alternatively the heat transfer element may be directly supported from the floor or other surface exteriorly of the heater, by means of the spindle or rod 41 extending vertically through the central air inlet port 34a of the gas burner 34 and also downwardly through the lower heater chamber 26.

In assembling the apparatus the heat transfer element 40 including its loosely supporting spindle 41 is first projected into the heating tube 20 through the door aperture 26a. The burner element 34 is next inserted into the chamber 26 so as to rest upon the transverse rod 36 in the manner hereinbefore described. The outer doors 26b may then be closed to substantially enclose the burner unit in its inserted position as best illustrated in Fig. 4.

For the purpose of vertically adjusting the heat transfer element 40 relative to the heating tube and burner to vary the vertical extent of the combustion space 27, the nut 45 may be threaded on spindle 41 so as to support the transfer element in any desired vertical position within the heating tube 20. This adjustment may be performed prior to inserting the transfer element within the heater, or by first lowering the burner so that access to said nut 45 may be obtained through the door opening 26a.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

What I claim is:

1. A gas fired water heater, comprising a water storage tank having a vertical open ended tube

extending therethrough to provide an uptake passage for combustion products, a heat transfer element mounted in the lower portion of said tube and including a central body of less cross-sectional area than that of said tube and having a closed wall to prevent passage of combustion products through said body, said heat transfer element including said closed wall defining the upper end of a combustion space extending transversely of said tube between said heat transfer element and the lower tube end, said body having angularly disposed vanes on the exterior thereof extending in close proximity to the tube wall to conduct said combustion products thereagainst and thence through said uptake passage, and a gas burner disposed substantially centrally of the bottom of said tube to fire directly upwardly into said combustion space, the flame emitting area of said burner not exceeding the cross-sectional dimensions of said tube.

2. A gas fired water heater, comprising a water storage tank having a vertical open ended tube extending therethrough to provide an uptake passage for combustion products, a heat transfer element mounted in the lower portion of said tube and including a central cylindrical body of less cross-sectional area than that of said tube and having a closed wall to prevent passage of combustion products through said body, said heat transfer element including said closed wall defining the upper end of a combustion space extending transversely of said tube between said element and the lower tube end, a plurality of helically disposed vanes on the exterior of said cylindrical body extending in close proximity to the tube wall to conduct said combustion products thereagainst and thence vertically through said uptake passage, and a gas burner disposed substantially centrally of and beneath the bottom of said tube to fire directly upwardly into said combustion space and providing for ready access of secondary air to support the combustion of the burner flame, the flame emitting area of said burner not exceeding the cross-sectional dimensions of said tube.

3. A gas fired water heater, comprising a water storage tank having a vertical open ended tube extending therethrough to provide an uptake passage for combustion products, means enclosing said tank in spaced relation thereto to provide an annular downtake passage therebetween communicating at its upper end with said uptake passage and communicating at its lower portion with a flue outlet, a heat transfer element mounted in the lower portion of said tube and including a central body of less cross-sectional area than that of said tube and having a closed wall to prevent passage of combustion products through said body, said heat transfer element including said closed body wall defining the upper end of a combustion space extending transversely of said tube between said element and the lower tube end, said body having angularly disposed vanes on the exterior thereof extending in close proximity to the tube wall to conduct said combustion products thereagainst and thence through said uptake passage, and a gas burner disposed substantially centrally of the bottom of said tube to fire directly upwardly into said combustion space, the flame emitting area of said burner not exceeding the cross-sectional dimensions of said tube, whereby combustion products in said space are directed upwardly between the vanes of said heat transfer element and the tube wall to effectively heat the

water in the lower tank portion, said combustion products thereafter passing upwardly through said tube and over the top of the tank and thence downwardly through said annular downtake passage surrounding the tank to said flue outlet, thereby most efficiently utilizing the heat in said combustion products to uniformly and rapidly heat the water in the tank.

4. A gas fired water heater, comprising a water storage tank having a vertical open ended tube extending therethrough to provide an uptake passage for combustion products, means enclosing said tank in spaced relation thereto to provide an annular downtake passage therebetween communicating at its upper end with said uptake passage and communicating at its lower portion with a flue outlet, a heat transfer element mounted in the lower portion of said tube and including a central hollow cylindrical body of less diameter than said tube, said body having a closed bottom to prevent upward passage of combustion products through said body and having helically disposed vanes on the exterior thereof extending in close proximity to the tube wall to conduct said combustion products thereagainst and thence vertically through said uptake passage, said heat transfer element including said closed bottom defining the upper end of a combustion space extending transversely of said tube between said element and the lower tube end, and a gas burner disposed centrally of the bottom of said tube to fire directly upwardly into said combustion space, the flame emitting area of said burner not exceeding the cross-sectional dimensions of said tube, said burner being spaced from the bottom of the tube for ready access of secondary air to support combustion of the burner flame, whereby the combustion products in said space are directed upwardly between the vanes of said heat transfer element and the tube wall to effectively heat the water in the lower tank portion, said combustion products thereafter passing upwardly through said tube uptake passage and over the top of the tank and thence downwardly through said annular surrounding downtake passage to said flue outlet, thereby most efficiently utilizing the heat of said combustion products to uniformly and rapidly heat the water in the tank.

5. A gas fired water heater, comprising a water storage tank having a vertical open ended tube extending therethrough to provide an uptake passage for combustion products, a heat transfer element mounted for vertical movement in the lower portion of said tube and including a central cylindrical body of less diameter than said tube and having a closed bottom wall to prevent passage of combustion products therethrough, said heat transfer element including said closed wall defining the upper end of a combustion space extending transversely of said tube between said element and the lower tube end, said body having helically disposed vanes on the exterior thereof extending in close proximity to the tube wall to conduct said combustion products thereagainst and thence vertically through said uptake passage, a gas burner disposed substantially centrally of the bottom of said tube to fire directly upwardly into said combustion space, the flame emitting area of said burner not exceeding the cross-sectional dimensions of said tube, said burner being spaced beneath the bottom of the tube wall for ready access of secondary air to support combustion of the burner flame, and means for adjusting the height of said heat transfer element relative to said burner for varying the volume of said combustion space within said tube.
